(57) **CLAIM**

We claim the ornamental design for a plastic bottle, as shown and described.

DESCRIPTION

FIG. 1 is a front perspective view of a plastic bottle showing the present invention.

FIG. 2 is a side elevation view of the bottle shown in FIG. 1, all sides being identical.

FIG. 3 is a plan view from the top of FIG. 2; and,

FIG. 4 is a plan view from the bottom of FIG. 2.

The broken line showing in the drawings is for illustrative purposes only and forms no part of the claimed design.
